LASTING MACHINE

Lloyd G. Miller, Beverly, Mass., assignor to United
Shoe Machinery Corporation, Flemington, N.J.,
a corporation of New Jersey

Application January 18, 1950, Serial No. 139,298

16 Claims. (Cl. 12—1)

1

This invention relates to lasting machines, and particularly to a novel and improved machine for progressively tensioning different portions of the stock being lasted; successively, in different locations along the marginal edge of the bottom of a shoe and for laying the lasting margin of each tensioned portion of the stock inwardly over, and pressing it against, the bottom of the shoe in each location to secure it in lasted position by means of an adhesive. It will be understood, however, that the invention in its broader aspects is not limited to use in machines for lasting with an adhesive or in a lasting machine of the exact mechanical construction herein illustrated.

It is an object of this invention to provide a novel and improved machine for lasting shoes progressively, that is of relatively simple construction yet easy to operate and effective in use. To this end, the herein illustrated machine has novel tensioning means comprising a power-operated reciprocating jaw, for engaging one side of the stock to be lasted, and a second yieldably mounted jaw for engaging the other side of the lasting margin and cooperating with the first jaw to seize, tension, and release portions of the lasting margin of the stock, successively, in different locations along the marginal edge of the bottom of a shoe as the shoe is moved past these jaws. More particularly, and in accordance with a feature of the invention, power-operated means are also provided for imparting movements to the second jaw in directions extending toward and away from and laterally of the first jaw, in predetermined time relation to the reciprocations of the first jaw so that these jaws will cooperate in a more effective manner to seize, tension and release the different portions of the lasting margin of the stock.

With the view of simplifying the construction, and also to improve the wiping action, the first-mentioned jaw and a wiper are carried by a reciprocating slide which is urged yieldingly in a direction to hold the wiper down on the lasting margin during movement of the slide in one direction, toward the shoe, and means are provided for raising the slide to elevate the wiper above the bottom of the shoe when the slide is moved in the opposite direction, away from the shoe. More particularly, the first-mentioned jaw is yieldingly urged in a direction to clamp the lasting margin against the second yieldably mounted jaw during a portion of the movement of the slide in a direction toward the shoe, and

2

cam means are provided for moving the first jaw away from clamping position during a subsequent portion of its movement in this direction. The movements of the second jaw, in directions toward and away from and laterally of the first jaw occur in predetermined time relation to the reciprocations of the slide and also to the movements of the first jaw toward and away from clamping position. Hence, these jaws not only cooperate to seize, tension and release portions of the lasting margin, successively, in different locations along the marginal edge of the bottom of the shoe, as the shoe is moved past the jaws, but also the wiper lays the lasting margin of the tensioned stock inwardly over, and presses it against, the bottom of the shoe in each location all as a continuous and progressive operation. Although the shoe being lasted may be moved along by the operator, preferably a mechanical feed is provided. In the herein illustrated machine, the mechanical feed is effected by an edge guide roll which is driven at a low speed so as to feed the shoe slowly past the jaws and the wiper.

25 When lasting with an adhesive, applied to the inside surface of the lasting margin of the stock and/or to the marginal portion of the shoe bottom, it is imperative that the lasting margin of the tensioned stock be pressed very firmly against the bottom of the shoe. If the lasting operation proceeds continuously along the marginal edge of the bottom of the shoe, the pressing action of a wiper is necessarily of somewhat limited duration and hence alone may not be sufficient to effect a secure bonding of the lasted margin of the stock to the shoe bottom. Also, after a shoe has been lasted, and before a sole-attaching adhesive can be applied thereto, the exposed surface of the lasting margin of the stock must be abraded, or otherwise roughened. 30 Accordingly, means are provided for applying additional pressure to the overlaid lasting margin, to augment its adherence to the bottom of the shoe, and this means is also utilized for abrading the exposed surface of the lasting margin so as to prepare it for the reception of sole-attaching adhesive. Thus, the herein illustrated machine has a rotary roughing brush arranged to engage the exposed surface of the lasting margin immediately after the lasting margin has 35 been laid inwardly over, and pressed against, the bottom of the shoe by the wiper.

40 These and other objects and features of the invention will appear in the following detailed 45 description of the preferred embodiment there-

50

of illustrated in the accompanying drawing and will be pointed out in the claims.

Fig. 1 is a view in side elevation of a lasting machine embodying the features of this invention;

Fig. 2 is a view in front elevation of the machine shown in Fig. 1;

Fig. 3 is a plan view of the machine with certain parts in section;

Fig. 4 is a plan view of a portion of the machine with certain parts in section substantially on line IV—IV of Fig. 1; and

Figs. 5 through 8 are views of the operating elements of the machine which, together with Fig. 1, illustrate the different positions assumed by these elements during an operating cycle.

Referring to the drawings, and particularly Figs. 1 and 5-8 thereof, the machine therein illustrated is provided with a gripper comprising jaws 10 and 12 for tensioning the stock being lasted and for drawing its lasting margin in over the bottom of the shoe, a reciprocating wiper 14 for wiping the lasting margin of the tensioned stock inwardly from the edge of the shoe bottom and for pressing it against the shoe bottom, and a rotary brush 16 for abrading and roughing the exposed surface of the lasting margin after it has been tensioned and secured to the bottom of the shoe and for applying additional pressure to the lasting margin. During the operation of the machine the shoe is held in the hands of an operator and positioned, relatively to the aforementioned operating elements, by engagement with an edge guide roll 18 and a guard member 20 that also serves as a bottom rest. A deflecting finger 22 is also provided for holding the lasting margin of the stock in a position to be engaged by the gripper jaws 10, 12.

The gripper jaw 10 is formed on the lower end of an arm 24 which is adjustably secured to a bar 26 by means of a screw 28 and the bar 26 is, in turn, adjustably secured, by a screw 30, to an arm 32 that is formed integrally with an elongated hub portion 34, Fig. 1. This hub portion is splined to a sleeve 36 that is rotatably mounted on a stud shaft 38 which is secured to an upstanding portion 40 of a frame 42, Fig. 2. Formed integrally with the sleeve 36 is a rearwardly extending arm 44 carrying a cam roll 46 that is adapted to contact a cam track 48 formed on a cam 50. The cam 50 is secured to a vertical shaft 52 that is journaled in horizontally extending portions 54, 56 of the frame portion 40, Figs. 1 and 2. The hub 34 is provided with two spaced ears 58, 60, Fig. 3, between which is located the rounded end 62 of a lever 64. This lever is pivotally mounted on a stud 66, carried by a bracket member 68 that is formed integrally with the frame portion 40, and at its other end carries a cam roll 70. This cam roll is arranged to engage an eccentric 72, secured to the shaft 52 and having a portion thereof enclosed by an arcuate rib 74, Figs. 1 and 3. The arm 24 is formed with an ear 76 and stretched between a pin 78 in this ear and a pin 80, carried by the bracket 68, is a tension spring 82.

With the arrangement already described, the jaw 10 may be swung outwardly and upwardly, about the axis of the stud shaft 38 and against the resistance of the spring 82, either by the action of the cam 50 or by the other jaw 12 and in a manner to be explained. Also, the jaw 10 may, at a predetermined time in the operating cycle, be moved transversely of the jaw 12 and in a direction lengthwise of the shoe by the action

of the eccentric 72 and a coil spring 84 that is stretched between an eye 86, on the lever 64, and an eye 88 on the frame portion 40, Fig. 3, as will be apparent from the drawings. Thus the jaw 10 may cooperate with the jaw 12 for intermittently seizing, tensioning and releasing different portions of the lasting margin of the stock, successively, along the margin of the bottom of a shoe.

The jaw 12 is pivotally mounted on the wiper 14 by means of a stud 90 and is provided with a cam roll 92 and a spring abutment 94, Figs. 5, 6 and 7. A compression spring 96 is interposed between the abutment 94 and an adjusting screw 98, threaded through a bracket 100 that is associated with the wiper 14. When the wiper is reciprocated, in a manner to be described below, the cam roll 92, at times, comes into contact with a cam plate 102 that is secured to a curved arm 104 mounted on a post 106 by means of a screw 107. This post extends upwardly from the frame member 54, see Figs. 1 and 2. When the cam roll 92 engages the cam plate 102, the jaw 12 will be rotated about the axis of the stud 90 in a clockwise direction as illustrated in Figs. 5 and 6 for a purpose that will presently appear.

The wiper 14 is mounted on one end of a slide 110 that is mounted for reciprocation in slide-carrying bracket 112. This bracket has an upstanding arm 114 and is pivotally mounted on a pin 115 that is carried by a boss 116 formed on the frame member 54, Fig. 1. The slide 110 has two ears 118, which are provided with slots 119 to receive the ends of the pin 115, and carries a stud 120 on which is mounted a spherically shaped cam roll 122. This roll is held against a cam 124, secured to the shaft 52, by means of a pair of coil springs 126, 126 which are stretched between the ends of the pin 115 and the ends of a second pin 126 that passes through the slide 110. The cam 124 is so shaped that for every revolution of the shaft 52 the slide 110, and the jaw 12 and wiper 14 carried thereby, are reciprocated by being moved to the left, as viewed in Figs. 1, 3-7, by this cam and then returned by means of the springs 126, 126. The wiper 14 operates during the movement of the slide 110 to the left to wipe the lasting margin of the stock inwardly over, and to press it against, the bottom of the shoe. On the return movement of the slide to the right, the slide is elevated to lift the wiper up away from the bottom of the shoe to prevent unlusting of the stock in the following manner.

Also pivoted on the boss 116 by means of a pin 130, carried by the boss 116, is a yoke member 132 having a pair of arms 134, 136, Fig. 4. At their outer ends, these arms carry a pair of rolls 138, 140 which bear against and support the left-hand end of the slide 110 and the slide-carrying bracket 112. The arm 136 also carries a cam roll 142 that engages a cam track 144 formed in a cam 146 that is secured to the shaft 52, Fig. 1. The cam track 144 is so shaped and angularly disposed with respect to the cam 124 that just as the slide 110 is about to be returned by the springs 126, 126, it is elevated by the cam 146 so as to hold the wiper up away from the bottom of the shoe. However, before the slide 110 is again moved to the left by the cam 124, it is lowered so as to bring the wiper 14 into operative position by the action of a coil spring 150. This spring is stretched between the upstanding arm 114, on the slide-carrying bracket 112, and an ear 152 that is formed on the frame portion 56.

The slide 110 is cut away at 154, Fig. 4, so as to slide over a square bushing 156 through which the shaft 52 extends.

The shaft 52 is driven in the direction of the arrow, Fig. 3, in the following manner. A main power shaft 160, which is journaled in a bushing 162, pressed into the frame portion 40, and by a bearing post 163, is provided with a belt pulley 164 to which power may be supplied from a motor, not shown, by means of a belt 166. The shaft 160 also carries a second belt pulley 168, which, as will be explained below, drives the rotary brush 16, and a bevel gear 170. This bevel gear drives the shaft 52 through bevel gears 172, 174, 176, 178 and 180 and shafts 182, 184, as will be clear from Fig. 1. The bevel gear 180 is secured to the shaft 52 which also carries a spur gear 186. The edge guide roll 18, which is rotatably mounted on the frame member 54, is driven by the spur gear 186 through spur gears 188, 190, 192, 194 and 196 and shafts 198 and 200, as will be clear from Figs. 1, 2 and 3.

The rotary brush 16 is carried by a shaft 220 which is mounted in ball bearings 222, 224, fitted in a boss 226 that is formed on one end of an arm 228, Fig. 3. This arm is pivotally mounted, at its other end, on an enlarged portion 230 of the bushing 162. The shaft 220 carries a pulley 232 which is driven from the pulley 168 by means of a belt 234. Threaded into a boss 236, formed on the arm 228, is a clamping bolt 238 which passes through an arcuate slot 240 which is concentric with the axis of the bushing 162, cut through the frame member 40 and an interior boss 242 thereon. When the clamping bolt 238 is loosened, the arm 228 may be swung about the axis of the bushing 162, and also of the pulley 168, for the purpose of adjusting the vertical position of the rotary brush 16 without, however, effecting the tension of the belt 234.

The guard member 20 is arcuate in shape, Figs. 5-7, and is formed integrally with a block 250, Fig. 1. This block is adjustably secured to the end of a laterally extending boss 252, Fig. 3, formed in the arm 228, by means of a clamping bolt 254, which passes through a slot 256 in the block 250, Fig. 1. The deflecting finger 22, which is formed in the shape of a hook, is secured to the upper side of the arm 104 by means of a screw 258, Fig. 4.

The construction of the several operating elements having been described, the operation of the machine will now be explained with particular reference to Figs. 1 and 5 to 8 of the drawings. In these figures the machine is shown as lasting the platform cover C of a so-called platform, or slip-lasting, shoe comprising an upper U assembled on a last L, together with a platform P and a sock lining S. It will be understood, however, that the herein illustrated machine is not only capable of but is intended for use in the lasting of the uppers of conventional shoes in the same manner as it operates on the cover C. With the machine running, the shoe to be lasted is presented to the machine by an operator who inserts the lasting margin of the cover C behind the finger 22, in a position to be engaged by the gripper jaws 10 and 12, and holds the shoe with the bottom of the platform P up against the rotary brush 16 and guard member 20 and with the edge of the platform P and a portion of the cover C bearing against the edge guide roll 18.

As the slide 110, carrying the wiper 14 and the gripper jaw 12, is rapidly reciprocated, the fol-

lowing actions occur. First, the lasting margin of the cover C is clamped firmly between the jaws 10, 12, Fig. 1, and the jaw 10 is swung about the axis of the stud 38 and against the resistance of spring 82 by the continued movement of the jaw 12. This movement of the jaws 10, 12 tensions the cover and draws its lasting margin inwardly over the bottom of the platform P, the parts soon reaching the positions shown in Fig. 5. Just as the wiper 14 comes into engagement with the lasting margin of the cover C and begins its wiping action, the jaws 10 and 12 are separated by the actions of the cam 50 and cam block 102, so that when the slide 110 completes its movement to the left the parts reach the positions shown in Fig. 6 with the lasting margin of the cover C wiped in over, and pressed against, the bottom of the platform P by the wiper 14. It will be understood that the inside surface of the lasting margin of the cover C and/or the marginal edge of the bottom of the platform P will have previously been coated with a suitable adhesive so that the lasting margin is securely fastened to the platform in lasted position by the pressing action of the wiper 14. The slide 110 and wiper 14 are now elevated as shown in Fig. 7, against the action of spring 150 by the cam 144 and returned to their starting position by the springs 126 as permitted by cam 124. While the slide 110 and wiper 14 are thus being returned, the jaw 12 is lowered by the spring 96 to the position shown in Fig. 1. At the same time, the jaw 10 is likewise returned to its original position.

However, in thus returning, the jaw 10 is also shifted in directions extending laterally of the jaw 12 and lengthwise of the shoe, by the eccentric 72 and spring 84, in time relation to its movement toward the jaw 12 and laterally of the shoe which is effected by the spring 82 when permitted by cam 50. These several movements are so timed that the jaw 10 is first moved in a direction lengthwise of the shoe and laterally away from the jaw 12 by the eccentric 72, then swung about the axis of the stud 38, by spring 82 as permitted by cam 50, in a direction toward the edge of the bottom of the shoe and toward the jaw 12, and finally the jaw 10 is returned to its original position in line with the jaw 12 by movement lengthwise of the shoe which is effected by the action of the spring 84 and the enclosed portion 14 on the eccentric 72. Thus the jaw 10 is inserted beneath the cover C in a location where its lasting margin is somewhat elevated above the bottom of the shoe and is then moved yieldingly in a direction lengthwise of the shoe beneath the lasting margin to a position in line with the jaw 12, see solid and dotted line showing of the jaw 10 in Fig. 8. This arrangement assures that the jaw 10 will certainly slide under the lasting margin into a position to cooperate with the jaw 12 in seizing and tensioning the cover C.

As will be apparent from Fig. 4, the wiper 14 operates directly in line with the jaw 12. Hence the shoe must be fed along between each reciprocation of the slide 110 so as to present an unlasted and unwiped portion of the lasting margin of the cover C to the action of the jaws 10, 12 and the wiper 14. While the operator could, if desired, effect such movement of the shoe manually, a much more even feeding of the shoe, and consequently a more uniform lasting action, may be obtained if the shoe is fed mechanically. In the herein illustrated machine, this mechanical feeding is obtained by means of the edge guide

roll 18. This guide roll is preferably provided with a soft rubber facing 280 for better frictional engagement with the edge of the platform P and interposed portion of the cover C, see Figs. 5 to 8. The guide roll 18 is rotated from the main power shaft 160 in the manner explained above and at a low speed. Hence, as this roll rotates in the direction of the arrow, Fig. 8, the shoe will be fed along at a uniform and relatively slow speed so that different portions of the lasting margin of the cover C are successively presented to the actions of the jaws 10, 12 and wiper 14. Thus the lasting operation will proceed, continuously, along the periphery of the bottom of the shoe as long as the operator holds the edge of the shoe against the guide roll 18. When the lasting operation is completed, the operator merely moves the shoe away from the guide roll 18 and downwardly out of the machine.

As the lasting operation proceeds, the lasting margin of the cover C, after it has been wiped in over and pressed against the bottom of the platform by the wiper 14, is acted on by the rotary brush 16. This brush not only abrades, or roughs, the exposed surface of the lasting margin of the cover C, but also exerts considerable pressure thereon. This additional pressure augments the adhesive bond between the lasting margin and the platform and in this manner improves the lasting action of the machine as a whole. Moreover, the shoe is already prepared, as a result of the roughing action of the brush 16, for the application of a sole-attaching adhesive. In order to avoid premature adherence of the lasting margin of the cover C to the shoe bottom at the beginning of the lasting operation, the operator may first hold the shoe in a position with its bottom inclined away from the rotary brush 16 and then swing the shoe up into operating position, after it has been fed along far enough to bring a tensioned and overwiped portion of the lasting margin into the zone of action of the brush. By adjusting the position of the guard member 20, relatively to the brush 16, by means of clamping bolt 254, the intensity of the abrading action of the brush 16 may be varied at will. Also, by adjusting the arm 228 the heightwise position of the brush 16 and hence of the guard member 20, which also serves as a bottom rest in the manner illustrated in Fig. 7, may be varied to change the position of the work in a heightwise direction relatively to the gripper jaws 10, 12 and the wiper 14. If desired, and as shown in the herein illustrative machine, the operating surface of the guard member 20 may be provided with a series of teeth 300, Figs. 5 to 7, which will bite into the wiped over lasting margin of the cover and thus facilitate the holding of the shoe in operating position against the pulling action of the jaws 10, 12.

Having thus described the invention, what is claimed as new and desired to secure by Letters Patent of the United States is:

1. A lasting machine having tensioning means comprising a power-operated reciprocating gripper jaw for engaging one side of the lasting margin of the stock to be lasted, a second gripper jaw for engaging the other side of said lasting margin, and power-operated means for imparting movements to the second jaw in directions extending toward and away from and laterally of the first jaw in predetermined time relation to the reciprocating movements of said first jaw, to cause said jaws to seize, tension and release different portions of the lasting margin, successive-

ly in different locations, along the marginal edge of the bottom of a shoe as said shoe is moved past said jaws.

2. A lasting machine having tensioning means comprising a power-operated reciprocating gripper jaw for engaging one side of the lasting margin of the stock to be lasted, a second yieldably mounted gripper jaw for engaging the other side of said lasting margin, and power-operated means for imparting movements to the second jaw in directions extending toward and away from and laterally of the first jaw, in predetermined time relation to the reciprocating movements of said first jaw, to cause said jaws to seize, tension and release different portions of the lasting margin, successively, in different locations along the marginal edge of the bottom of a shoe as said shoe is moved past said jaws.

3. A lasting machine having tensioning means comprising a power-operated reciprocating slide carrying a gripper jaw for engaging one side of the lasting margin of the stock to be lasted, a second gripper jaw for engaging the other side of said lasting margin, and power-operated means for imparting movements to the second jaw in directions extending toward and away from and laterally of the first jaw, in predetermined time relation to the reciprocating movements of said slide, to cause said jaws to seize, tension and release different portions of the lasting margin, successively, in different locations along the marginal edge of the bottom of a shoe as said shoe is moved past said jaws.

4. A lasting machine having tensioning means comprising a power-operated reciprocating slide carrying a gripper jaw for engaging one side of the lasting margin of the stock to be lasted, a second yieldably mounted gripper jaw for engaging the other side of said lasting margin, and power-operated means for imparting movements to the second jaw in directions extending toward and away from and laterally of the first jaw, in predetermined time relation to the reciprocating movements of said slide, to cause said jaws to seize, tension and release different portions of the lasting margin, successively, in different locations along the marginal edge of the bottom of a shoe as said shoe is moved past said jaws.

5. A lasting machine having a power-operated reciprocating slide carrying a wiper and a gripper jaw for engaging one side of the lasting margin of the stock to be lasted, a second gripper jaw for engaging the other side of said lasting margin, and power-operated means for imparting movements to the second jaw in directions extending toward and away from and laterally of the first jaw, in predetermined time relation to the reciprocating movements of said slide, to cause said jaws to seize, tension and release different portions of the lasting margin, successively, in different locations along the marginal edge of the bottom of a shoe and said wiper to lay the lasting margin of the tensioned stock inwardly over, and to press said lasting margin against, the bottom of the shoe in each location as said shoe is moved past the jaws and the wiper.

6. A lasting machine having a power-operated reciprocating slide carrying a wiper and a gripper jaw for engaging one side of the lasting margin of the stock to be lasted, a second yieldably mounted gripper jaw for engaging the other side of said lasting margin, and power-operated means for imparting movements to the second jaw toward and away from and laterally of the

first jaw, in predetermined time relation to the reciprocating movements of said slide, to cause said jaws to seize, tension and release different portions of the lasting margin, successively, in different locations along the marginal edge of the bottom of a shoe and said wiper to lay the lasting margin of the tensioned stock inwardly over, and to press said lasting margin against, the bottom of the shoe in each location as said shoe is moved past the jaws and the wiper.

7. A lasting machine having a power-operated reciprocating slide carrying a gripper jaw for engaging one side of the lasting margin of the stock to be lasted, a second gripper jaw for engaging the other side of said lasting margin, said first jaw being yieldingly held in a position to clamp the lasting margin against the second jaw during a portion of the movement of the slide in one direction, means for moving the first jaw away from clamping position during a subsequent portion of its movement in said direction, and power-operated means for moving said second jaw in directions extending toward and away from the first jaw, in predetermined time relation to the reciprocating movements of said slide and to the movements of said first jaw, to cause said jaws to seize, tension and release different portions of the lasting margin, successively, in different locations along the marginal edge of the bottom of a shoe as the shoe is moved past the jaws.

8. A lasting machine having a power-operated reciprocating slide carrying a gripper jaw for engaging one side of the lasting margin of the stock to be lasted, a second gripper jaw for engaging the other side of said lasting margin, said first jaw being yieldingly held in a position to clamp the lasting margin against the second jaw during a portion of the movement of the slide in one direction, means for moving the first jaw away from clamping position during a subsequent portion of its movement in said direction, and power-operated means for moving said second jaw in directions extending toward and away from and laterally of the first jaw, in predetermined time relation to the reciprocating movements of said slide and to the movements of said first jaw, to cause said jaws to seize, tension and release different portions of the lasting margin, successively, in different locations along the marginal edge of the bottom of a shoe as the shoe is moved past the jaws.

9. A lasting machine having a power-operated reciprocating slide carrying a gripper jaw for engaging one side of the lasting margin of the stock to be lasted, a second yieldably mounted gripper jaw for engaging the other side of said lasting margin, said first jaw being yieldingly held in a position to clamp the lasting margin against the second jaw during a portion of the movement of the slide in one direction, means for moving the first jaw away from clamping position during a subsequent portion of its movement in said direction, and power-operated means for moving said second jaw in directions extending toward and away from the first jaw, in predetermined time relation to the reciprocating movements of said slide and to the movements of said first jaw, to cause said jaws to seize, tension and release different portions of the lasting margin, successively, in different locations along the marginal edge of the bottom of a shoe as the shoe is moved past the jaws.

10. A lasting machine having a power-operated reciprocating slide carrying a gripper jaw for

engaging one side of the lasting margin of the stock to be lasted, a second yieldably mounted gripper jaw, for engaging the other side of said lasting margin, said first jaw being yieldingly held in a position to clamp the lasting margin against the second jaw during a portion of the movement of the slide in one direction, means for moving the first jaw away from clamping position during a subsequent portion of its movement

10 in said direction, and power-operated means for moving said second jaw in directions extending toward and away from and laterally of the first jaw, in predetermined time relation to the reciprocating movements of said slide and to the movements of said first jaw to cause said jaws to seize, tension and release different portions of the lasting margin, successively, in different locations along the marginal edge of the bottom of a shoe as the shoe is moved past the jaws.

11. A lasting machine having a power-operated reciprocating slide carrying a wiper and a gripper jaw for engaging one side of the lasting margin of the stock to be lasted, a second gripper jaw for engaging the other side of said lasting margin, said first jaw being yieldingly urged to a position to clamp the lasting margin against the second jaw during a portion of the movement of the slide in one direction, means for moving the first jaw away from clamping position during a subsequent portion of its movement in said direction, and power-operated means for moving said second jaw in directions extending toward and away from the first jaw, in predetermined time relation to the reciprocating movements of said slide and to the movements of said first jaw, to cause said jaws to seize, tension and release different portions of the lasting margin, successively, in different locations along the marginal edge of the bottom of a shoe and said wiper to lay the lasting margin of the tensioned stock inwardly over, and to press said lasting margin against, the bottom of the shoe in each location as the shoe is moved past the jaws and the wiper.

12. A lasting machine having a power-operated slide carrying a wiper and a gripper jaw for engaging one side of the lasting margin of the stock to be lasted, a second gripper jaw for engaging the other side of said lasting margin, said first jaw being yieldingly urged to a position to clamp the lasting margin against the second jaw during a portion of the movement of the slide in one direction, means for moving the first jaw away from clamping position during a subsequent portion of its movement in said direction, and power-operated means for moving said second jaw in directions extending toward and away from and laterally of the first jaw, in predetermined time relation to the reciprocating movements of said slide and to the movements of said first jaw to cause said jaws to seize, tension and release different portions of the lasting margin, successively, in different locations along the marginal edge of the bottom of a shoe and said wiper to lay the lasting margin of the tensioned stock inwardly over, and to press said lasting margin against, the bottom of the shoe in each location as the shoe is moved past the jaws and the wiper.

13. A lasting machine having a power-operated reciprocating slide carrying a wiper and a gripper jaw for engaging one side of the lasting margin of the stock to be lasted, a second yieldably mounted gripper jaw for engaging the other side of said lasting margin, said first jaw being yieldingly urged to a position to clamp the lasting margin against the second jaw

during a portion of the movement of the slide in one direction, means for moving the first jaw away from clamping position during a subsequent portion of its movement in said direction, and power-operated means for moving said second jaw in directions extending toward and away from the first jaw, in predetermined time relation to the reciprocating movements of said slide and to the movements of said first jaw, to cause said jaws to seize, tension and release different portions of the lasting margin, successively, in different locations along the margin of the bottom of a shoe and said wiper to lay the lasting margin of the tensioned stock inwardly over, and to press said lasting margin against, the bottom of the shoe in each location as the shoe is moved past the jaws and the wiper.

14. A lasting machine having a power-operated reciprocating slide carrying a wiper and a gripper jaw for engaging one side of the lasting margin of the stock to be lasted, a second yieldably mounted gripper jaw for engaging the other side of said lasting margin, said first jaw being yieldingly urged to a position to clamp the lasting margin against the second jaw during a portion of the movement of the slide in one direction, means for moving the first jaw away from clamping position during a subsequent portion of its movement in said direction, and power-operated means for moving said second jaw in directions extending toward and away from and laterally of the first jaw, in predetermined time relation to the reciprocating movements of said slide and to the movements of said first jaw, to cause said jaws to seize, tension and release different portions of the lasting margin, successively, in different locations along the margin of the bottom of the shoe and said wiper to lay the lasting margin of the tensioned stock inwardly over, and to press said lasting margin against, the bottom of the shoe in each location as the shoe is moved past the jaws and the wiper.

15. A lasting machine having a power-operated reciprocating slide carrying a gripper jaw, a second gripper jaw for cooperating with the first-mentioned jaw to seize, tension and re-

lease different portions of the lasting margin of the stock to be lasted, successively, in different locations along the marginal edge of the bottom of a shoe as the shoe is moved past the jaws, a wiper carried by the slide and arranged to lay the lasting margin of the stock inwardly over, and to press said lasting margin against, the bottom of the shoe in each location when the slide is moved in one direction, spring means for urging the slide in a direction to hold the wiper yieldingly down on the lasting margin during movement of the slide in said direction, and means for raising the slide to elevate the wiper above the shoe bottom when the slide is moved in the opposite direction.

16. A lasting machine having a power-operated reciprocating slide carrying a gripper jaw, a second gripper jaw for cooperating with the first-mentioned jaw to seize, tension and release different portions of the lasting margin of the stock to be lasted, successively, in different locations along the marginal edge of the bottom of a shoe as the shoe is moved past the jaws, a wiper carried by the slide and arranged to lay the lasting margin of the stock inwardly over, and to press said lasting margin against, the bottom of the shoe in each location when the slide is moved in one direction, spring means for urging the slide in a direction to hold the wiper yieldingly down on the lasting margin during movement of the slide in said direction, and cam-operated means for raising the slide to elevate the wiper above the shoe bottom when the slide is moved in the opposite direction.
